Reference is had to my prior U.S. Patent No. 2,183,320, dated Dec. 12, 1939, for a description of the invention and the drawings thereon, which are incorporated herein by reference.

UNITED STATES PATENT OFFICE

2,218,440

DOUBLE-ACTION DOOR AND HINGE STRUCTURE

Folkert C. Schoneman, Aplington, Iowa

Application March 25, 1940, Serial No. 325,900

5 Claims. (Cl. 20—16)

This invention relates to door structures and more particularly to a double-acting door for use in hog houses or sheep sheds which is so constructed that the animals may easily push the door to an open position from either side thereof, and at the same time, the door will gravitatingly swing to a normally closed position.

An object of this invention is to provide a door structure of this kind which can be easily and quickly mounted in a door opening, the device including a pair of door members which are hinged together and also hingedly secured to the door frame structure.

Another object of this invention is to provide in a door structure of this kind, a pair of swinging door members which are hingedly connected together and which includes means whereby one of the door members is limited in its swinging movement relative to the other door member.

A further object of this invention is to provide a novel means for swingably suspending one door member from another and also swingably suspending the other door member within a door frame.

A still further object of this invention is to provide a door mounting means which is adapted to be secured to a pair of door members, the mounting means being relatively simple in construction so that it will not readily get out of order under rough usage.

To the foregoing objects and to others which may hereinafter appear, the invention consists of the novel construction, combination and arrangement of parts as will be more specifically referred to and illustrated in the accompanying drawing wherein are shown embodiments of the invention, but it is to be understood that changes, variations and modifications may be resorted to which fall within the scope of the invention as claimed.

40 In the drawing:

Figure 1 is a detail front elevation of a door structure embodying this invention which is swingably mounted in a door frame.

Figure 2 is a sectional view taken on the line 45 2—2 of Figure 1.

Figure 3 is an enlarged fragmentary sectional view taken on the line 3—3 of Figure 1.

Figure 4 is an enlarged fragmentary sectional view taken on the line 4—4 of Figure 1.

Figure 5 is an enlarged fragmentary sectional view taken on the line 5—5 of Figure 1.

Referring to the drawing, the numeral 10 designates generally a door frame structure including a pair of side frame members 11, an upper rail or horizontal frame bar 12 and a sill 13.

An upper door member 14 is disposed between the two side members 11 closely adjacent the rail or upper frame member 12 and is swingably disposed between the side members 11 by a mounting means which includes a pair of vertically disposed channel members 15. The channel members 15 are of U-shaped or L-shaped configuration and an attaching plate 16 is welded adjacent its outer edge to one side 17 of the channel member 15.

The plate 16 is secured to one face of the upper door member 14 by fastening devices 18 which may be in the form of rivets, bolts or the like. The upper end portion of each channel member 15 is swingably secured to a vertical frame member 11 by means of a pivot 19 in the form of a lag screw or the like which extends through the bight 20 of the channel member 15. The channel member 15 extends downwardly from the upper door member 14 and engages in a cut-out portion 21 which is cut out from a lower door member 22.

An L-shaped strip 23 has one side 24 thereof secured as by fastening devices 25 to one face of the lower door member 22 and the other leg 26 of the L-shaped member 23 is provided with an opening 27 through which a headed pivot member 28 engages. The bight 20 of the channel member 15 is provided with a plurality of spaced apart openings 29 which extend upwardly from the lower end thereof and the pintle or pivot member 28 is adapted to engage through a selected one of the openings 29. A cotter pin 30 is extended transversely through the pintle or pin 28 and engages within the channel formed between the two sides 17 and 31 of the channel member 15.

The leg 26 of the L-shaped member 23 extends outwardly of the opposite side or face of the door 40 22 to which the supporting member 23 is secured extending through a recess or slot 32 which is formed in an edge of the lower door member 22. The terminal end of the leg 26 is provided with a right angularly disposed stop member 33 which is adapted to engage the channel member 15 45 when the lower door member 22 is rocked upwardly from its lower end in one direction so as to thereby limit the swinging movement of the lower door member 22 relative to the swinging channel members 15.

In the use and operation of this double-action door structure, the channel members 15 are swingably secured between the side members 11 of the door frame structure 10 by securing the lag bolts 19 in the frame members 11. The upper 50 65

5 pivot members 19 are disposed above the center of the upper door member 14 and in like manner the pintles or pivot members 28 are mounted in a position above the center of the lower door member 22 so that these two door members will gravitatively swing back to a vertical position. Preferably the lower door member 22 is substantially longer than the upper door member 14 so that when the small animals desire to go one 10 way or the other through the door opening formed by the frame 10, the animals may push the lower portion of the lower door member 22 thereby swinging this lower door member on the pintles or pivot members 28.

15 In the event the animals are not able to pass through the door opening formed by the lower door member 22, additional pressure on the lower door member 22 will cause the stop member 33 to engage the channel member 15 above the pintle 28 and effect an outward swinging of the channel members 15 together with an outward swinging of the upper door member 14.

25 A door structure and mounting means constructed according to this invention may be manufactured at a relatively small cost and the component parts of the mounting means are so constructed that they can withstand considerable hard usage before getting out of order.

30 Furthermore, by providing a double-acting door structure and a mounting means therefor as hereinbefore described, the door frame structure may have the opening thereof maintained in a normally closed position but animals may easily and quickly pass through the door opening by pushing against the lower door so as to effect a swinging of this door in addition to a swinging of the upper door 14 where the lower door 22 will not provide sufficient opening for the animals to pass through the door frame
35 40 opening.

What I claim is:

1. A double-acting door structure and mounting means therefor comprising an upper door member, a lower door member, a pair of depending suspension members disposed at the opposite vertical edges of said door members, means fixedly securing the upper portions of said suspension members to said upper door member, pivot means engaging the upper portions of said suspension members pivotally supporting said suspension members, means pivotally securing said lower door member to the lower portions of said suspension members, and means carried by said lower door engageable with said suspension members to limit the swinging movement of said lower door in one direction.

60 2. A double-acting door structure and mounting means therefor comprising an upper door member, a lower door member, a pair of elongated suspension members U-shaped in transverse section, a plate fixed to one side of a suspension member, means securing said plates to said upper door member, means pivotally supporting said suspension members, a pair of L-shaped members, means engaging one side of said L-shaped members securing said latter

65

members to said lower door, said suspension members having a plurality of spaced openings in the bights thereof, and a pintle engaging through the other side of an L-shaped member and in a selected opening of suspension member pivotally securing said lower door member to said suspension members.

3. A double-acting door structure and mounting means therefor comprising an upper door member, a lower door member, a pair of elongated suspension members U-shaped in transverse section, a plate fixed to one side of a suspension member, means securing said plates to said upper door member, means pivotally supporting said suspension members, a pair of L-shaped members, means engaging one side of said L-shaped members securing said latter members to said lower door, said suspension members having a plurality of spaced openings in the bights thereof, a pintle engaging through the other side of an L-shaped member and in a selected opening of a suspension member pivotally securing said lower door member to said suspension members, and a right angularly disposed extension carried by the said other side of an L-shaped member disposed in the path of a suspension member to thereby limit the swinging movement of said lower door member relative to said upper door member.

4. A mounting means for a pair of upper and lower vertically swingable doors comprising a pair of suspension members each including an elongated member U-shaped in transverse section and provided at one end thereof with an opening to receive a pivot member for the upper door, 35 a plate fixed to one side of said elongated member provided with openings to receive fastening devices for securing the plate to the upper door, said elongated member having a plurality of spaced openings in the bight thereof adjacent the opposite end thereof, an L-shaped lower door supporting member provided with openings in one side thereof to receive attaching devices for securing said one side to the lower door, a pintle 40 engaging through the other side of said supporting member and a selected one of said spaced openings in the bight of said elongated member, and a right angularly disposed stop member carried by said other side of said L-shaped member engageable with said elongated member to limit 45 the swinging of the lower door in one direction relative to said upper door. 50

5. A double-acting door structure and mounting means therefor comprising an upper door member, a lower door member, a pair of depending suspension members disposed at the opposite vertical edges of said door members, means fixedly securing the upper portions of said suspension members to said upper door member, pivot means engaging the upper portions of said suspension members pivotally supporting said suspension members, and means pivotally securing said lower door member to the lower portions of said suspension members.
